PARTICLE SEPARATION UTILIZING A MAGNETIZED FLUID

Jack Green, La Habra, Calif., assignor to California Research Corporation, San Francisco, Calif., a corporation of Delaware

Application April 20, 1956, Serial No. 579,559

12 Claims. (Cl. 209—208)

This invention relates in general to particle separation and relates more particularly to the separation of particles of nonmagnetic or slightly magnetic materials according to either shape or density.

There are a number of methods and apparatus for separating particles of material. Such methods include the use of heavy liquids for separation on the basis of density, mechanical classifiers and elutriation devices for separation on the basis of size and density, various screening arrangements for separation on the basis of particle size, numerous magnetic separation systems for separating magnetic and nonmagnetic materials, and flotation methods for separating homopolar from non-homopolar substances.

There are numerous applications where precise separation of particles in accordance with their density and/or shape is required. One of such applications is in the separation of mineral particles in geochemical work and in standard mineral dressing techniques. For example, in some geochemical problems it may be desirable to separate zircons from a sand matrix, micas with inclusions from micas without inclusions, or clouded feldspars from unclouded feldspars. In mineral dressing practices it may be desirable to separate, say, iron-rich sphalerites from iron-free sphalerites, or possibly, cobalt-rich pyrite from pure pyrite. These separations, even using flotation methods, have heretofore been virtually impossible to perform at a reasonable cost and with speed and accuracy because of the minute differences in densities in many cases. The use of screens for such separations is not practical, owing to the fact that the volume of the different particles is not necessarily directly related to the density thereof. In addition to the above-listed examples of particle separation, there are numerous other applications in which it is desired to perform precise separation of nonmagnetic particles without resorting to laborious manual sorting.

Broadly the present invention contemplates methods and apparatus for separating nonmagnetic particles according to density and shape parameters in which the material is placed in a substantially vertical tube which contains a suspension of a magnetic material colloidally dispersed in a suitable liquid. A first electromagnetic coil disposed along the length of the tube produces a first electromagnetic field in the colloidal suspension, and the strength of this electromagnetic field varies progressively along the length of the tube. The electromagnetic field reacts with the magnetic particles in the colloidal suspension to vary the viscosity of the fluid as a function of the strength of this electromagnetic field. This phenomenon of varying the viscosity of a colloidal suspension containing magnetic particles in response to the application of an electromagnetic field is fairly well known, and is utilized in the so-called "magnetic fluid clutch" and other similar applications.

In one embodiment, the spiral coil winding of the first electromagnetic coil is so disposed that the viscosity of the colloidal suspension progressively increases down-

2

wardly of the tube. The material to be separated is then introduced into the top of the column of solution, and the nonmagnetic particles distribute themselves in the variable viscosity, colloidal suspension at a rate determined by their density. According to the nature of the material to be separated, approximate or discrete size fractions may be prepared by screening prior to introduction of the material into the tube, although in some cases this step may not be necessary. This method is particularly effective in certain geochemical applications in which it produces an exaggerated separation of low density, layer lattice mineral particles, such as micas, with respect to the high density nonlayer lattice minerals, such as garnets. After a suitable time period, an optimum degree of separation of the different particles occurs. The length of this period will be dependent upon the characteristics of the electromagnetic field, which characteristics may be varied at will, the properties of the iron-fluid colloidal suspension and the shape and density parameters of the material to be separated.

When the optimum separation has been reached, an additional set of secondary electromagnetic coils is energized to produce a plurality of localized electromagnetic fields at different zones along the length of the tube. These localized electromagnetic fields are of considerably greater magnitude than the first electromagnetic field, and they act to effectively solidify the colloidal suspension into a plurality of spaced "disks," each disk having a location corresponding to a zone of application of a respective secondary field. This solidification physically segregates the fractions which have already been separated by the variable viscosity of the colloidal suspension. The first electromagnetic field is then removed and the colloidal suspension together with the entrained particles of nonmagnetic material is drawn out of the tube at one or more points between the solidified disks to obtain the desired density fraction or fractions of the separated nonmagnetic particles. For some materials, separation of constituents may occur as a function of shape. The separated material is then collected on a suitable filter or screen which permits the iron-fluid colloidal suspension to pass through into a recirculating unit. As an additional refinement of the present invention, the drawn-off solution may be subjected to an additional electromagnetic field which removes any magnetic particles present in the colloidal suspension.

The objects and advantages of the present invention will be further apparent from the following description when read in connection with the accompanying drawing, the single figure of which diagrammatically illustrates one embodiment of the present invention.

Referring to the drawing by character of reference, numeral 11 designates a hollow tube of suitable material, such as glass, Bakelite, aluminum, or steel, in which the suspension is disposed. Tube 11 is provided with an opening at the top thereof for the introduction from a hopper 20 of the material to be separated. According to the nature of the material to be separated, approximate or discrete size fractions of the material are prepared by screenings, although in some cases this step may not be necessary. Tube 11 may be provided at its lower end with a conduit 12 leading to a filter and recirculation pump. Tube 11 is filled, preferably to the top thereof, with a colloidal suspension 13 comprising particles of a highly magnetic material, such as iron, colloidally dispersed in a suitable liquid such as glycerine, oil, water, silicone oil, or kerosene. The initial concentration of iron in suspension may be varied to produce a series of iron suspensions which may be used according to the gross density-shape parameters of the material to be separated. Care should be taken to avoid the

presence of any chemically reactive substances, such as sulphur, in the suspending fluid. In some instances, the dispersion of magnetic particles in the suspending fluid may result in a settling and caking of the magnetic particles over a period of time. To avoid this, the magnetic particles may be treated with a wetting agent which surrounds each particle with a layer of fluid, so that a slight mixing of the dispersion results in a homogenous mixture.

Tube 11 is surrounded along its length by a first electromagnetic coil 16. The spacing between the turns of coil 16 progressively decreases downwardly of tubing 11 so that the strength of the electromagnetic field produced in colloidal suspension 13 by coil 16 will progressively increase downwardly of tube 11. Coil 16 is energized from a suitable source of current such as a battery 21 connected to a potentiometer 22. The electromagnetic field produced by coil 16 magnetizes the magnetic particles in colloidal suspension 13 to cause the viscosity of colloidal suspension 13 to progressively increase in the direction of the progressively increasing electromagnetic field.

A plurality of secondary electromagnetic coils 23a, 23b, 23c, 23d, and 23e surround tube 11 at spaced zones along the length thereof. Coils 23a through 23e each preferably comprise only a few closely spaced turns so as to localize the effects of their electromagnetic fields at zones corresponding to the locations of the coils themselves. Coils 23a through 23e are energized in parallel from a suitable current source such as a battery 24 connected to a potentiometer 25. The current supplied to coils 23a through 23e is preferably several orders of magnitude greater than that supplied to coil 16. The currents in secondary coils 23a through 23e may be controlled independently of each other by means of individual adjustable resistors, as shown. In some cases it may be desirable to keep the currents in these coils at a level below that necessary to produce solid disks. For example, highly viscous disks may enhance the separation of substances of widely different density or shape parameters.

Tube 11 is also provided along its length with a plurality of outlet lines or spigots 26a, 26b, 26c, 26d, and 26e, which preferably extend into approximately the center of tube 11, for withdrawing selected portions of the colloidal suspension in tube 11. Suitable means are also provided for conducting the drawn-off solution from the spigot to a suitable container. Such means may be in the form of a sluice 27 communicating with a suitable sieve or filter 28 on which the separated fraction may collect, permitting the colloidal suspension to pass through and be recirculated through a funnel and conduit 33. An additional electromagnetic coil 31 connected to a battery 32 may be provided below sluice 27 for removing the magnetic particles in the drawn-off colloidal suspension. Although sluice 27, filter 28, coil 31, and recirculation conduit 33 have been illustrated only in connection with spigot 26c, it will be understood that similar means will be provided in association with the other spigots.

In operation of the embodiment illustrated in the drawing, after placing the colloidal solution or suspension of colloidally dispersed magnetic materials in tube 11, coil 16 is energized to produce an electromagnetic field in the colloidal suspension, the strength of this magnetic field progressively increasing in value downwardly of tube 11. This progressively increasing electromagnetic field produces a corresponding progressive increase in the viscosity of the solution downwardly of tube 11. The magnitude of the electromagnetic field of the spiral windings of coil 16 may be adjusted by means of the potentiometer 22 to make initial gross density separations, or may be so adjusted as to enhance separation according to the specific density-shape parameters of the material to be separated. When desired, this adjustment

may be accomplished gradually and automatically during the separation process by adjustment of potentiometer 22.

The material to be sorted is then introduced into the top of tube 11 from hopper 20 and permitted to distribute itself in the variable viscosity solution at a rate in accordance with the density and/or shape of the non-magnetic particles. After an optimum time period when the desired separation of particles in the variable viscosity or colloidal suspension is reached, coils 23a through 23e are energized to provide localized electromagnetic fields of high intensity at the locations of these coils. These coils effectively solidify the colloidal suspension into a plurality of disks at zones along the length of tube 11 corresponding to the location of coils 23a through 23e. These disks form effective physical barriers between which the material to be separated is distributed in density and/or shape fractions.

After this solidification, coil 16 may be deenergized and one or more of spigots 26a through 26e may be opened to draw off the colloidal suspension to obtain the desired density and/or shape fraction. In this connection, suitable stoppered openings (not shown) may be provided in tube 11 to permit the entry of air during drainage of the different fractions.

Stokes' law of fluid mechanics relates the density and size of a particle to the density and viscosity of the fluid in which the particle falls:

$$V = \frac{2 \cdot g \cdot a^2 \cdot (d_1 - d_2)}{9\eta}$$

where:

V is velocity in cm./sec.

g is acceleration due to gravity in cm./sec.²

a is the radius of the particle considered as a sphere

d₁ is the density of the particle

d₂ is the density of the medium

η is the coefficient of viscosity of the medium.

As a consequence of this law and the fact that the viscosity of the medium will progressively increase downwardly in tube 11, progressively denser fractions of particles may be withdrawn from spigots 26a, 26b, 26c, 26d, and 26e, respectively, per unit time. Similarly, it will be obvious that for a given length of tube 11, the number and spacing of coils 23a through 23e will determine the number of different density fractions obtainable, as well as the density range within a given fraction. Also, for a given length of tube 11 the number and spacing of coils 23a through 23e will determine, for certain materials, both the number of different fractions obtainable based on shape parameters and the index of sphericity range within a given fraction. Furthermore, the fields produced by coils 23a through 23e are localized as much as possible to produce as thin disks as practical. As the solution is drawn off, electromagnetic coil 31 may be energized from battery 32 to magnetically remove the magnetic particles in the drawn-off solution.

In an alternate embodiment of the present invention, the direction of variation of the strength of the first electromagnetic field is reversed with respect to its direction of variation in the embodiment illustrated in the drawing. That is, the turns of the coil are more closely spaced at the top of the tube than at the bottom, thus producing an electromagnetic field which increases in strength upwardly in the tube and resulting in a progressive increase in the viscosity of the magnetized solution upwardly in the tube. In this case, the material to be separated is introduced into the top of the tube and permitted to settle at a rate determined by the density and space parameters of the particles. The separation is performed on a rate of settling basis by energizing the secondary electromagnetic coils at a predetermined time after introduction of the material in the tube. The time interval between introduction and energization will be dependent upon the degree of separation required, the characteristics of the separated material and the viscosity

gradient existing in the solution, the important point being that the reversed viscosity gradient produces an exaggerated separation of the particles on the basis of density and shape parameters, and that a suitable time interval can be selected which will result in the desired degree of separation.

Although but a few illustrative embodiments of the present invention have been described, it will be apparent to those skilled in the art that various changes and modifications may be made therein without departing from the spirit of the invention or the scope of the appended claims.

I claim,

1. The method of separating particles of a non-magnetic material according to density and shape parameters comprising the steps of forming a column of a suspension of particles of a magnetic material colloidally dispersed in a liquid, applying a first electromagnetic field to said suspension to magnetize said particles of magnetic material, varying the strength of said first field along the length of said column to cause the viscosity of said suspension to vary progressively along the length of said column, inserting said particles of a nonmagnetic material in the top of said column to cause said particles of a nonmagnetic material to distribute themselves in said variable viscosity suspension in accordance with their density and shape parameters, applying a second electromagnetic field to at least two spaced-apart zones along the length of said column to effectively solidify said suspension at said zones, and withdrawing from said column the suspension and particles of nonmagnetic material between said effectively solidified zones.

2. The method of separating particles of a nonmagnetic material according to density and shape parameters comprising the steps of forming a column of a suspension of particles of a magnetic material colloidally dispersed in a liquid, applying a first electromagnetic field to said suspension to magnetize said particles of magnetic material, varying the strength of said first field along the length of said column to cause the viscosity of said suspension to vary progressively along the length of said column, inserting said particles of nonmagnetic material to be separated in the top of said column to cause said particles of nonmagnetic material to be distributed in said variable viscosity suspension in accordance with their density and shape parameters, applying a second electromagnetic field to at least two spaced-apart zones along the length of said column to effectively solidify said suspension at said zones, withdrawing from said column the portions of said suspension and particles of nonmagnetic material between said effectively solidified zones, and removing from said withdrawn portions the nonmagnetic particles contained therein.

3. The method of separating particles of a nonmagnetic material according to density and shape parameters comprising the steps of forming a column of a suspension of magnetic material colloidally dispersed in a liquid, applying a first electromagnetic field to said suspension, varying the strength of said first field along the length of said column to cause the viscosity of said suspension to vary progressively along the length of said column, inserting said particles to be separated in the top of said column to cause said particles to fall through said variable viscosity suspension at a rate determined by their density and shape parameters, applying a second electromagnetic field to at least two spaced-apart zones along the length of said column at a predetermined time after the introduction into said column of said particles to be separated to effectively solidify said suspension at said zones, and withdrawing from said column the suspension and particles of nonmagnetic material between said effectively solidified zones.

4. The method of separating particles of a nonmagnetic material according to density and shape parameters comprising the steps of forming a substantially vertical

column of a suspension of magnetic material colloidally dispersed in a liquid, applying a first electromagnetic field to said suspension, increasing said first field in strength upwardly along said column to cause the viscosity of said suspension to increase upwardly along said column, inserting said particles to be separated in the top of said column to cause said particles to fall through said variable viscosity suspension at a rate determined by their density and shape parameters, applying a second electromagnetic field to at least two spaced-apart zones along the length of said column at a predetermined time after the introduction into said column of said particles to be separated to effectively solidify said suspension at said zones, and withdrawing from said column the suspension and particles of nonmagnetic material between said effectively solidified zones.

5. Apparatus for separating particles of a nonmagnetic material according to density and shape parameters comprising a tube containing a suspension of magnetic material colloidally dispersed in a liquid, a first electromagnetic coil disposed along the length of said tube for producing an electromagnetic field in said suspension, means for varying the strength of said electromagnetic field along the length of said tube to cause the viscosity of said suspension to vary progressively along the length of said tube, means for introducing said particles of nonmagnetic material in said tube to cause said particles of nonmagnetic material to be distributed in said variable viscosity suspension in accordance with their density and shape parameters, a plurality of second electromagnetic coils disposed about said tube at zones spaced along the length thereof, means for energizing said second coils to produce a plurality of spaced electromagnetic fields which effectively solidify said suspension into a plurality of discs at said zones, and means for withdrawing from said tube the portion of said suspension and particles of nonmagnetic material between said discs.

6. Apparatus for separating particles of a nonmagnetic material according to density and shape parameters comprising a tube containing a suspension of magnetic material colloidally dispersed in a liquid, a first electromagnetic coil disposed along the length of said tube for producing an electromagnetic field in said suspension, means for varying the strength of said electromagnetic field along the length of said tube to cause the viscosity of said suspension to vary progressively along the length of said tube, means for introducing said nonmagnetic material in said tube to cause said nonmagnetic material to distribute itself in said variable viscosity suspension in accordance with its density and shape parameters, a plurality of second electromagnetic coils disposed about said tube at zones spaced along the length thereof, means for energizing said second coils to produce a plurality of spaced electromagnetic fields which effectively solidify said suspension into a plurality of discs at said zones, means for withdrawing from said tube the portion of said suspension, and particles of nonmagnetic material between said discs, and means for separating said particles of nonmagnetic material from said suspension in said withdrawn portion.

7. Apparatus for separating particles of a nonmagnetic material according to density and shape parameters comprising a tube containing a suspension of magnetic material colloidally dispersed in a liquid, a first electromagnetic coil disposed along the length of said tube for producing an electromagnetic field in said suspension, means for varying the strength of said electromagnetic field along the length of said tube to cause the viscosity of said suspension to vary progressively along the length of said tube, means for introducing said nonmagnetic material in said tube to cause said nonmagnetic material to be distributed in said variable viscosity suspension in accordance with its density and shape parameters, a plurality of second electromagnetic coils disposed about said tube at zones spaced along the length thereof, means for

energizing said second coils to produce a plurality of spaced electromagnetic fields of greater strength than said first field to effectively solidify said suspension into a plurality of discs at said zones, and means for withdrawing from said tube the portion of said suspension and particles of nonmagnetic material between said discs.

8. Apparatus for separating particles of a nonmagnetic material according to density and shape parameters comprising a nonmagnetic tube containing a suspension of magnetic material colloidally dispersed in a liquid, a first electromagnetic coil disposed along the length of said tube for producing an electromagnetic field in said suspension, means for varying the strength of said electromagnetic field along the length of said tube to cause the viscosity of said suspension to vary progressively along the length of said tube, means for introducing said nonmagnetic material in said tube to cause said nonmagnetic material to distribute itself in said variable viscosity suspension in accordance with its density and shape parameters, a plurality of second electromagnetic coils disposed about said tube at zones spaced along the length thereof, means for energizing said second coils to produce a plurality of spaced electromagnetic fields which effectively solidify said suspension into a plurality of discs at said zones, and a plurality of spigots on said tube between said second coils for withdrawing from said tube the portions of said suspension and particles of nonmagnetic material between said discs.

9. Apparatus for separating particles of a nonmagnetic material according to density and shape parameters comprising a tube containing a suspension of magnetic material colloidally dispersed in a liquid, a first electromagnetic coil disposed along the length of said tube for producing an electromagnetic field in said suspension, means for varying the strength of said electromagnetic field along the length of said tube to cause the viscosity of said suspension to vary progressively along the length of said tube, means for introducing said nonmagnetic material in said tube to cause said nonmagnetic material to distribute itself in said variable viscosity suspension in accordance with its density and shape parameters, a plurality of second electromagnetic coils disposed about said tube at zones spaced along the length thereof, means for energizing said second coils to produce a plurality of spaced electromagnetic fields which effectively solidify said suspension into a plurality of discs at said zones, a plurality of spigots in said tube between said second coils for withdrawing from said tube the portions of said suspension and particles of nonmagnetic material between said discs, electromagnetic separation means for removing said magnetic material from said withdrawn suspension, and means for separating said nonmagnetic particles from said liquid.

10. Apparatus for separating particles of a nonmagnetic material according to density and shape parameters comprising a tube containing a suspension of magnetic material colloidally dispersed in a liquid, a first electromagnetic coil disposed along the length of said tube for

producing an electromagnetic field in said suspension, means for varying the strength of said electromagnetic field along the length of said tube to cause the viscosity of said suspension to vary progressively along the length of said tube, means for introducing said particles of nonmagnetic material in said tube to cause said nonmagnetic material to be distributed in said variable viscosity suspension in accordance with its density and shape parameters, a plurality of second electromagnetic coils disposed about said tube at zones spaced along the length thereof, means for energizing said second coils to produce a plurality of spaced electromagnetic fields which increase the viscosity of said suspension at said zones, and means for withdrawing from said tube the portion of said suspension and particles of nonmagnetic material between said zones.

11. The method of separating particles of a nonmagnetic material according to density and shape parameters comprising the steps of forming a column of a suspension of a magnetic material colloidally dispersed in a liquid, applying a first electromagnetic field to said suspension, varying the strength of said first field along the length of said column to cause the viscosity of said suspension to vary progressively along the length of said column, introducing said material to be separated in the top of said column to cause said nonmagnetic material to distribute itself in said variable viscosity suspension in accordance with its density and shape, applying a second electromagnetic field to at least two spaced-apart zones along the length of said column to increase the viscosity of said suspension at said zones, and withdrawing from said column the suspension and particles of nonmagnetic material between said zones.

12. The method of separating particles of a nonmagnetic material according to density and shape parameters comprising the steps of forming a column of a suspension of magnetic material colloidally dispersed in a liquid, applying a first electromagnetic field to said suspension, varying the strength of said first field along the length of said column to cause the viscosity of said suspension to vary progressively along the length of said column, inserting said material to be separated in the top of said column to cause said particles to distribute themselves in said variable viscosity suspension in accordance with their density and shape, varying the strength of said first field as said particles distribute themselves in said suspension, applying a second electromagnetic field to at least two spaced-apart zones along the length of said column to effectively solidify said suspension at said zones, and withdrawing from said column the suspension and particles of nonmagnetic material between said effectively solidified zones.
